UNITED STATES PATENT OFFICE.

CLIFFORD NORTON, OF NEW YORK, N. Y., ASSIGNOR TO GRAHAM & NORTON COMPANY, OF NEW YORK, N. Y., A CORPORATION OF DELAWARE.

ELECTROMECHANICAL INTERLOCK.

Original application filed August 2, 1923, Serial No. 655,175. Divided and this application filed January 10, 1925. Serial No. 1,569.

To all whom it may concern:

Be it known that I, CLIFFORD NORTON, a citizen of the United States, and a resident of New York, in the county of New York and State of New York, have invented certain new and useful Improvements in Electromechanical Interlocks, of which the following is a specification.

My invention relates to a door closing and opening apparatus of the class wherein a pair of toggle arms or levers or other devices are employed for moving a door such as an elevator door or elevator well door from open to closed position and vice versa by the use of applied manual or other power.

This application is a division of applicant's co-pending application Serial No. 655,175, filed August 2, 1923.

The invention is designed to provide for the opening and closing of an elevator well door by the use of magnetic means on the car in such manner that while the car is running the door operating apparatus will be locked against operation and whereby the operation of the car by electric or similar power is rendered impossible when the door has been opened.

The invention as embodied in the special apparatus herein described is particularly useful in connection with electric push-button systems of elevator control and operation and the invention will therefore be described as applied to that use.

The invention consists essentially in the combination with the door opening and closing mechanism of a latch which serves to lock a member thereof in the door closed position of the parts, a power controlling switch consisting of a circuit-closer and breaker controlling the application of the electric power employed to move the elevator in any of the well known ways, and operating means for actuating the latch and switch simultaneously to free the door opening and closing mechanism when the door is to be opened and at the same time rendering it impossible to move the elevator car, said operating means being operable from the car when it is at a landing through the operation of a device magnetically controlled on the car.

The invention consists also in the particular combinations of devices and details of construction hereinafter more particularly described and then specified in the claim.

Fig. 1 is a general side elevation of the door operating mechanism, latch and switch in one of the forms that my invention may take.

Fig. 2 is an edge view of the same and shows in addition the means on the car employed in combination therewith, the car being shown with its floor level with the landing floor.

Fig. 3 shows in detail the toggle arm catch and the actuating switch in enlarged view.

1 indicates an elevator well door which may be of the sliding type. The door closing and opening mechanism is here shown as of the toggle arm type although the invention may be applied likewise to other forms employing a lever or levers for imparting movement to the door. One of said arms 2 is pivoted, as indicated, to the sliding door and the other 2' is pivoted at a fixed bracket or abutment secured to a studing or wall of the elevator shaft or otherwise fixedly supported. The toggle arm system or levers thereof are pivotally connected together as at 3 and as well understood in the art. The levers of the toggle arm system may be arranged with relation to one another so as to permit the joint of the toggle to be broken by moving the door, or they may be so arranged with relation to one another that the arms will lie in the same line intersecting the toggle joint and so that they will in effect operate to lock the door against movement by an extraneous force applied to the door and until the toggle is broken by power applied to one of the members thereof. It is therefore to be understood that the toggle may be operated in any of the ways well understood in the art.

As indicated, a handle 4 may be provided to break the toggle for the purpose of opening the door or said toggle may be operated by means of a cylinder 5 connected therewith as well understood in the art. In the case of the latter device the power may be

pneumatic or other power or may be power stored in a spring acting on a piston within the cylinder 5 when the handle 4 or other device is used to apply power in the opening of the door.

The device here shown is of the general type described in the Norton Patent No. 1,124,941, dated January 12, 1915, embodying in addition to the spring a suitable liquid check or dashpot at its lower end which comes into action when the spring operates to close the door. The device 5, however, is to be understood as being merely illustrative of any means for applying pneumatic or other power in the opening or closing movement or both, said device being suitably connected to the lever arm 2' by a pivotal or other connection.

Applied to some part of the door opening and closing mechanism, as for instance, to an arm 2' of the toggle, is a catch or locking device indicated at 7 and shown for illustration as a latch or lever. Said latch is pivotally mounted at 8 on a fixed support such as the wall of the elevator shaft or studding and at its free end is a locking shoulder 7' adapted to rest upon and lockingly engage a stud or arm 8' carried by the toggle arm 2'. Obviously said latch operates to prevent the arm 2' from swinging upward in the arc of a circle which it must do in order that the toggle may carry the door 1 back from the closed position indicated in Fig. 1 and in the direction of the arrow 9 in order to open the door. Gravity or a spring may serve to normally hold or assist in holding the locking catch 7 in the normal position shown. When, however, said catch is raised to free the arm 2' the latter may swing upwardly in the door opening movement.

29 indicates the casing of an interlocking switch of any desired type or form applied to act on an operating or controlling circuit of the motive power by which the car is moved in such a manner that in one position of the switch the car may be moved by manual or automatic control while in the other position the apparatus is rendered inoperative to move the car. The manner of connecting a switch having this function into the circuits is well understood in the art and need not be further particularly described. Circuit wires for said switch are indicated at 10, 10'. The operating member of said switch, which member may be of any desired form or form suited to the type of switch employed, is indicated at 12.

In the present instance I have shown my invention as carried out by the use of a type of switch substantially like that described in my application for patent filed February 2, 1923, Serial No. 616,485, and having two spring-pressed circuit closing members 11, 11' which normally tend to en-

gage one another and close the circuit of 10, 10'. A reciprocating bar or block of insulating material like "bakelite" or other suitable material constitutes the operating member 12 and is mounted in position between the circuit closing arms 11, 11' and is adapted to be forced between and separate said arms to break the circuit. In the normal position or circuit closing position said block or bar 12 occupies the position indicated in full lines in Fig. 3. Said block or other operating member of the switch is attached to link 12' and said link is preferably joined to the latch or an arm 14 extending therefrom by means adjustable if desired longitudinally to adjust the throw of the parts as indicated at 13. When it is desired to operate the toggle arms to open the door it is necessary to lift the latch 7 and in so doing the switch is operated to break the interlocking control circuit, thereby stopping or rendering it impossible to further operate the car by its motive power.

A bar or rod 6 suitably guided and working vertically in guides on the side of the elevator well opening operatively engages with the latch and power controlling switch in any desired way as for instance by means of a toe or head 6a adapted to engage and lift the latch when the rod is lifted. The switch may be simultaneously operated through any suitable means, as for instance the inter-connecting link 12' between the switch and the latch already referred to.

The bar 6 may be lifted by means of the bell crank lever 17 the horizontal member of which is connected to the bar while the depending vertical member thereof protrudes into position to be thrust sidewise by the cam or actuator 15 having a vertically elongated engaging surface adapted to be thrust sidewise against the vertical arm of the bell crank when the car is level with the landing, said actuating member being properly mounted and guided on the car. The position of said actuating member 15 is controlled by magnetic means on the car consisting, for instance, of an electric motor 25 which, when energized, operates a drum 26 which winds up a cord or chain connected with the cam and with a rod 27 that in the winding movement stores power in a compressible spring 28, as clearly indicated. While the magnetic device is energized the cam 15 is held retracted or in inoperative position but when the car reaches the floor level a change of circuit condition, automatic as in the push-button system of elevator control or otherwise resulting, de-energizes said motor and the spring 28 then operates to throw the actuating member 15 sidewise thereby, through the intermediate devices already described, bringing about simultaneous operation of the latch and of the power controlling switch so that the

door operating mechanism is free from the action of the latch and the door may then be opened.

- In this movement the pin or dog 8' moves under and supports the latch so that it may not drop back into locking position until the door is again closed. The action of freeing the latch, however, is accompanied by simultaneous action on the interlocking switch 10 that, being thrown, operates as before described to render the movement of the elevator away from the landing impossible, it being now impossible to apply the motive power to the elevator.
- 15 When however it is desired or permissible to move the car away from the landing, the magnetic device 25 is energized thus withdrawing the operating cam or member 15 from engagement with the bell crank so that 20 the bar 6 or other operating member acting on the latch and switch may drop. This allows the latch 7 and the interlocking or power controlling switch to resume normal position on closure of the door, the operating mechanism therefor being thereafter locked and held until again freed by the action of the cam device 15 operating to raise the latch.
- 25 As will be seen, the office of the electric motor 25 which is normally energized while the car is moving, is to hold the cam or other operating device in inoperative position by electromagnetic action and to free the same

for operation by the spring or other device when the car is at the selected landing, 35 through interruption of the charging circuit of the electromagnet by any desired means, automatic or otherwise, as for instance by the means usually employed in the operation of a push-button system of elevator control.

It is to be understood that the structure disclosed is merely illustrative and that the applicant is entitled to equivalents so long as they fall within the scope of the subject-matter claimed.

What I claim as my invention is:—

The combination with door opening and closing mechanism adapted to be controlled from an elevator car, of a latch engaging and holding a member thereof in door-closing position, operating means for operating said latch to free said mechanism, said means including a cam slidably supported for right line movement transverse to the path of movement of said car, spring means for moving said cam into position to free said latch, a rotary electric motor, a connecting member for operatively joining said cam and motor whereby said motor may draw said cam directly away from said latch.

Signed at New York in the county of New York and State of New York this 9th day of January A. D. 1925.

CLIFFORD NORTON.
